(57) **CLAIM**

The ornamental design for a juicer device, as shown and described.

DESCRIPTION

FIG. 1 shows a top right perspective view of a juicer device of my new design;

FIG. 2 shows a bottom left perspective view thereof;

FIG. 3 shows a top plan view thereof;

FIG. 4 shows a bottom plan view thereof;

FIG. 5 shows a right elevation view thereof;

FIG. 6 shows a left elevation view thereof;

FIG. 7 shows a front elevation view thereof;

FIG. 8 shows a back elevation view thereof;

FIG. 9 shows another top right perspective view of the juicer device in an open condition;

FIG. 10 shows a top left perspective view of the juicer device in another open condition;

FIG. 11 shows another top plan view thereof; and,

FIG. 12 shows another right elevation view thereof.

The broken lines depict portions of the juicer device that form no part of the claimed design.
